(57) **CLAIM**

The ornamental design for module with a plurality of illuminating elements, as shown and described.

DESCRIPTION

FIG. 1 is a top, front left side perspective view of a module with a plurality of illuminating elements showing my new design;

FIG. 2 is a left side elevation view thereof, the right side elevation view being a mirror image;

FIG. 3 is a rear elevation view thereof;

FIG. 4 is a front elevation view thereof;

FIG. 5 is a top plan view thereof; and,

FIG. 6 is a bottom plan view thereof.

Elements of the drawings shown in broken lines do not constitute a part of the claimed invention.
